UNITED STATES PATENT OFFICE

120,082

DESIGN FOR A COMBINED MAKE-UP BOX AND TIME CLOCK

Paul P. Paisner, Chicago, Ill.

Application February 7, 1940, Serial No. 90,085

Term of patent 3½ years

To all whom it may concern:

Be it known that I, Paul P. Paisner, a citizen of the United States, residing at Chicago, in the county of Cook and State of Illinois, have invented a new, original, and ornamental Design for a Combined Make-Up Box and Time Clock, of which the following is a specification, reference being had to the accompanying drawing, forming part thereof.

Fig. 1 is a perspective view and Figs. 2 and 3 are front and side elevational views, respectively, on slightly smaller scales, of a combined make-up box and time clock showing my design.

I claim:

The ornamental design for a combined make-up box and time clock, as shown.

PAUL P. PAISNER.
